UNITED STATES PATENT OFFICE.

JOHN KRALUND AND CLARENCE H. DUCKWORTH, OF BROOKLYN, NEW YORK, ASSIGNEES TO DOEHLER DIE CASTING COMPANY, OF BROOKLYN, NEW YORK, A CORPORATION OF NEW YORK.

DIE-CASTING APPARATUS.

Application filed February 9, 1921. Serial No. 443,533.

To all whom it may concern:

Be it known that we, JOHN KRALUND and CLARENCE H. DUCKWORTH, both citizens of the United States, and both residing in the 5 borough of Brooklyn, county of Kings, city and State of New York, have invented certain new and useful Improvements in Die-Casting Apparatus, of which the following is a specification.

10 Our invention relates to die-casting apparatus and particularly to improvements in the mechanism for supplying molten metal by air pressure from a melting pot to a suitable die or mold.

15 Our invention is an improvement on the type of structure described in patent to Kralund, 1,299,738, granted April 8, 1919. In the construction there described a swing- 20 ing or otherwise movable member, which may be termed a carrier or ladle, is made use of, this device dipping into the molten metal in the melting pot, so that a charge of the same runs into its interior, after which the carrier is moved to cause its mouth to register with the gate or opening of the die. As 25 soon as this is accomplished, compressed air is forced through the carrier to deliver the charge of the metal into the die.

Our present invention provides a plurality 30 of carrier devices of the character referred to which may be simultaneously operated to transfer charges of molten metal from a melting pot into a corresponding plurality of die openings. With such a construction a greater amount of molten metal may be 35 forced into a die, and consequently larger die castings may be produced by this method. Also a plurality of castings may be produced at one time in one machine. Two or more 40 carrier devices, operating in connection with a single molten metal container or melting pot, may be operated with the same amount of labor as in the case of a construction having a single carrier device, with a consequent economy of operation.

In accomplishing this result, the multiple carrier devices must be so mounted as to permit ready adjustment of the same in order that the mouths of the carrier devices shall 45 properly register with the gate openings of the dies. These gate openings may be positioned at different points, with respect to each other and with respect to the carrier devices, for different classes of work. By

our invention the various adjustments referred to may readily be made.

The object of our invention is to provide apparatus suitably arranged for producing the results above referred to in an effective manner, as will be more fully understood by reference to the following specification and appended claims.

In order that our invention may be more clearly understood, attention is hereby directed to the accompanying drawings forming part of this application and illustrating one form of our invention. In the drawings, Fig. 1 represents a vertical section taken on line 1—1 of Fig. 2; Fig. 2 is a top plan view of an apparatus embodying our invention, 70 equipped with a pair of ladle or carrier devices; Fig. 3 is a vertical section taken on line 3—3 of Fig. 1; Fig. 4 is an enlarged view partly in end elevation and partly in section of the compressed air connections for 75 one of the carrier devices illustrated; Fig. 5 is a vertical section on an enlarged scale taken on line 5—5 of Fig. 4; Fig. 6 is a partial enlarged vertical section of a carrier device and coacting parts as shown in Fig. 80 1; and Fig. 7 is an enlarged partial vertical section corresponding to the view illustrated in Fig. 3, showing certain details of construction.

Referring to the drawings, the melting 85 pot 1 is adapted to contain the main body of molten metal and is heated by any usual heating means in the heating chamber 2. The latter is preferably formed within a suitably fixed frame 3 having a transverse 90 rear flange portion 4 and longitudinal flange portions 5, 5.

A plurality of carrier devices or ladles 6, 6 are provided, two being used in the form of our invention illustrated in the drawings. 95 These carriers each have a hollow interior, terminating at the forward end in a mouth 7. The carriers may be of any suitable shape such as that shown, being closed at the rear, as by the closure 8, through which extends 100 a pipe connection 9 for the introduction of compressed air.

The carriers are supported by means enabling the mouths 7 thereof to be submerged into molten metal in container 1 in position 105 to permit the molten metal to readily flow into the same. The supporting means are adapted to raise the mouths of the carriers

thereafter, above container 1, and to project the same forwardly of the container 1 into registration with the gate openings of the die, which may be located immediately 5 above the edge of the melting pot.

In the preferred embodiment of our construction a shaft 10 extends transversely across container 1, this shaft being rotatably mounted at its opposite ends in brackets 11, 10 11, which extend upwardly from the side frame members 5. The carrier devices 6 are swingingly supported by links 12, the upper ends of which are mounted on shaft 10, while the lower ends of the links are provided 15 with transverse pins 13 over which extend yokes 14 on brackets 15 extending rearwardly from the carriers 6.

The carriers are provided with forwardly extending web portions 16 provided with 20 bosses or yokes 17 which are adapted to be mounted on arms or cranks 18. The latter are adapted to swing in vertical planes from the position shown in which the mouths of the carrier devices register with the gate 25 openings of the die, to a position in which arms 18 have swung downwardly to the rear, so that the mouths of the carriers will be submerged within the molten metal in the container 1.

30 Suitable means are preferably made use of for moving the plurality of carrier devices simultaneously from one position to the other, and for locking the carriers in their delivery positions in which their 35 mouths register with the gate openings of the die. Preferably, a toggle mechanism is used in connection with each carrier device, each toggle mechanism comprising a pair of links 19 and 20. Each link 19 is pivotally connected to the corresponding link 20 by means of a pin 21, the forward ends of links 20 being pivotally mounted on pins 13 which are carried by the links 12, on which are pivotally mounted brackets 15, as stated.

40 The rear ends of links 19 are mounted on a transverse shaft 22 for oscillation therewith. Shaft 22 may be oscillated by means of either hand lever 23, one of which is located on each side of the machine, so that oscillation of either hand lever will result in swinging the carrier devices simultaneously into their delivery positions, which are shown in Figs. 1 and 2, or into their opposite positions in which the mouths 7 are 45 submerged within the molten metal in container 1. Set screws 24 are mounted in flanges of links 19 to bear upon the upper surfaces of links 20, when the toggle joint is straightened, as shown in the drawings, to regulate the delivery positions of the carrier devices.

Transverse shaft 22 extends through and is rotatably mounted in a pair of adjustable frame members 25, 25 which are positioned 60 on the rear flange 4 of frame member 3. In

adjusting the positions of the carrier devices, members 25 may be properly adjusted independently of each other in the longitudinal direction of the machine. After such adjustment, screws 26, which extend 70 through upstanding bosses 27 on flange 4, may be adjusted in position to act as stops against which the rear edges of members 25 will engage.

The positions of members 25 transversely 75 of the apparatus may also be adjusted, independently of each other. Each member 25 is provided with slots 28 which extend transversely therethrough. Vertical bolts 29 extend through these slots, these bolts having heads at their lower ends which are adapted to engage against suitable shoulders on the lower surface of flange 4 of frame member 3. After frame members 25 have been suitably adjusted longitudinally and 85 transversely, bolts 29 are tightened to hold the same in their adjusted positions.

Members 25 are provided with cutouts 30 within which the rear ends of links 19 are mounted, so that these links, and the carrier 90 devices to which they are connected, will be moved with members 25 when the latter are adjusted in position.

Links 12 by which the carrier devices are swingingly supported are provided with longitudinal slots 31 therethrough which the shaft 10 extends. Adjusting screws 32 extend downwardly through the upper ends of links 12 into the slots 31. The lower ends of these screws bear against shaft 10, and accordingly support the carrier devices. These links may be positioned at any desired points along the length of shaft 10, and screw 32 may be adjusted up or down to vary the effective lengths of links 12. 100

The longitudinal flanges 5 of frame members 3 are provided with upwardly extending brackets or extensions 33, 33. Bearings 34 extend transversely from brackets 33 on each side of the same, and cranks 18 are rotatably mounted in these bearings. Each member 18 comprises a horizontal part 18' which extends through bearings 34 and a crank arm portion 18² which extends at an angle to the horizontal portion 18'. The inner end of each crank arm 18² is provided with a horizontal extension 18³ of reduced diameter which serves as a crank pin over which the boss 17 of one of the carrier devices engages. 110

The outer end of each member 18 extends 115 through a cross head 35 with which member 18 is arranged to move longitudinally, member 18 being, however, rotatable with respect thereto. Each cross head 35 is held in position by screws 36 which extend into one of the brackets or extensions 33. The position of each cross head 35, transversely of the apparatus, may be adjusted by means of nuts 37, 37 on the inner and outer sides of 120 125 130

the cross head 35, so that crank arms 18² will be adjusted transversely of the apparatus. Accordingly, the carrier devices may be adjusted at both the forward and rear 5 ends of the same, transversely of the apparatus, longitudinally of the same and vertically by the various adjusting means described.

The mouths of the carrier devices are 10 adapted as stated to deliver their charges into gate openings which may be provided in a gate member 38. The latter may be provided with a pair of openings, or with a plurality of openings equal to the number of 15 carrier devices employed, these openings being indicated at 39 in the drawings. Bushings 40 are mounted in openings 39, these bushings having bores through which the charges of molten metal are delivered by the 20 carrier devices.

The apparatus may be used in connection with a suitable die, a two part die being shown in the drawings, having parts 41 and 42. Die member 41 is suitably secured to 25 the gate member 38, so that the gate openings in die member 41 will align with the bores of bushings 40 in the gate member. Die member 42 is moved longitudinally of 30 the apparatus into contact with die member 41 and away from the same in opening and closing the die.

It is advisable that the gate openings in member 38 should be adjustable vertically and transversely of the apparatus with respect to the fixed frame member 3, so that 35 different conditions of operation in producing different sizes and variety of die castings, may be complied with.

In the form of our invention shown in 40 the drawings, gate member 38 is provided with slots 43 extending horizontally therethrough, these slots being elongated vertically. Bolts 44 extend through these slots and into the brackets or vertical extensions 45 33 of frame member 3. Gate member 38 may be adjusted to a desired vertical position, because of the relative movement of bolts 44 in slots 43, whereupon the bolts may 50 be tightened to secure the gate member to the frame member 3 in the desired position.

The gate member 38 is preferably provided with vertical adjusting screws 45 which extend downwardly through rearward extensions 46 of the gate member into 55 engagement with upper horizontal surfaces 47 formed at the forward ends of frame extensions 33. These screws 45 are properly set to bear against the fixed surfaces 47, when the gate member has been adjusted into proper vertical position.

Crank arms 18 may be provided at their outer ends with levers 48 for swinging the same independently whenever this may be desired.

65 The apparatus for opening and closing

the die may be of the general character of that described in Patent 1,300,739, Kralund, Duckworth and Stern, dated April 15, 1919. As stated, the die member 41 is removably secured to the gate member 38 in any suitable manner to cause registration between the openings through bushings 40 and the gate openings of die member 41. In the construction shown, the bushings 40 have rectangular outer surfaces and are mounted 70 in rectangular openings 39 in member 38, these openings being of greater lengths in a horizontal plane than the bushings. Accordingly, the bushings may be adjusted horizontally towards or away from each 75 other, in accordance with the distance between the gate openings in any die which will be used therewith. The bushings 40 may be held in adjusted position within 80 openings 39 by the tightness of the fit of the 85 upper and lower surfaces of the same within the openings, and by the coaction of the forward ends of the bushings with the gate openings in the die, the bushings preferably being provided with shoulder portions 49 90 at their forward ends which extend into corresponding recesses in the die member. The die is preferably closed by a mechanism such as that shown in the drawings, in which a power cylinder 50 is provided, this having 95 a piston 51 therein provided with a rod 52 extending rearwardly, that is, toward the melting pot 1, through a suitable gland. The piston or plunger 51 is reciprocated when desired by air or other suitable motive 100 fluid which may be admitted to the cylinder on opposite sides of the plunger by means of pipe connections 53 and 54.

The member 42 of the die which is 105 adapted to be moved into and out of engagement with the member 41 of the die when the die is to be opened or closed is suitably secured to the face of a ram or horizontally movable member 55 which is 110 preferably coaxial with cylinder 50.

Cylinder 50 is carried by a frame 56 having rearwardly extending upper and lower arms 57. Links 58 are pivotally connected to arms 57 to extend rearwardly therefrom. Links 59 are pivotally connected to ram 55 115 to extend forwardly therefrom, links 58 and 59 being pivotally connected together on pins 60 to form toggles. The rear end of piston rod 52 is pivotally connected to a block 61 which is connected by links 62, 62 120 to the pins 60. Accordingly, the rearward movement of plunger 51 into the position shown in the drawings serves to straighten out the toggles formed by links 58 and 59, to press the member 42 rearwardly into the 125 position in which the die is closed and is locked in closed position by the alignment of links 58 and 59. When the die is opened by causing plunger 51 to move forwardly, the toggles will be broken and the die 130

opened, member 42 being drawn forwardly through the connection of links 62 and 59.

Frame 56 is carried by a support which may be adjusted toward and away from the 5 melting pot 1. As shown, frame 56 may be carried by a standard 63 mounted on rollers 64 which are adapted to move on a platform 65. The longitudinal position of frame 56 is adjusted in accordance with the dimensions of the die members which are to be 10 used for any particular series of casting operations. This may be accomplished by providing frame 56 with bosses 66 through which extend the threaded tie rods 67, the 15 rear ends of which extend through openings in gate member 38, nuts 68 and 69 being mounted on the tie rods at the rear side of gate member 38 and at the forward and rear sides of bosses 66. Rods 67 may extend 20 through suitable sleeves 70 in the ram member 55, so that the latter will slidably move back and forth over rods 67.

Support 65 above which the ram mechanism is carried may be adjusted at different 25 desired heights by means of suitable mechanism such as the adjusting screws 71. Support 65 is carried by these screws, and as the latter are rotated in one direction or the other, support 65 will be raised or lowered 30 so as to raise or lower the mechanism carrying die member 42, so that the latter may properly align with die member 41, when the latter and gate member 38 have been adjusted in a desired vertical position.

35 The preferred connections for admitting compressed air to the rear or upper ends of carrier devices 6 will now be described. Pipe 72 is connected to a suitable air supply and is connected to a valve chamber 40 73. A valve stem 74 carries a valve 75 which is normally pressed against its seat in a slidably mounted member 76 by means of spring 77. When air is to be admitted to the carrier devices, hand lever 78 is rocked 45 to press rod 74 inwardly.

This serves, first, to press valve 75 away from its seat so as to permit compressed air in the chamber 79 to pass through the 50 passageway 80 through member 76, the stem of valve 75 being slidably mounted in this passageway. The air which passes through passageway 80 will enter chamber 81 at the outer end of member 76. The air pressure on the inner and outer ends of member

55 76 will accordingly be balanced, member 76 being the main valve member of the construction. Upon a further inward movement of valve stem 74, the boss 82 on valve stem 74 will press against the outer face 60 of member 76 to push the same inwardly. The inner end of member 76 is normally seated against a seat in a partition 83 and the inward movement of the same just referred to opens a passage 84 in this partition 65 so as to permit air to flow through the

same from chamber 79 into the pipe connection 85 leading downwardly from the valve chamber.

A T-connection 86 at the lower end of pipe 85 carries the air into a pair of horizontally extending pipes 87, 87 which are closed on their outer ends as is shown at 70 88 in Fig. 4. Sleeves 89 are mounted on tubular members 87, the longitudinal positions of sleeves 89 being adjusted by means 75 of screws 90 which extend through the ends of the sleeves into the end portions 88 of members 87. Radial openings 91 in members 87 communicate with a longitudinal recess 92 formed on the inner surface of each 80 sleeve member, the lengths of recesses 92 being sufficient to permit a required longitudinal adjustment of the sleeve members on the tubular members. Suitable glands 93 are used to keep the construction air-tight. 85

Sleeves 89 are provided with downwardly extending portions 94 through which extend passages 95 which communicate with recesses 92. Sleeves 89 are rotatably mounted on members 87. 90

Pipe connections 96 extend downwardly from the lower ends of passages 95 and are connected by elbows 97 with tubular members 98 which extend in horizontal alignment. Sleeves 99 are rotatably mounted on tubular members 98 in the same manner as sleeves 89 are mounted on tubular members 87. Radial openings 100 in tubular members 98 conduct the air into longitudinal recesses 101 provided in sleeve members 99. 100

Vertical pipe connections 102 extend downwardly from sleeves 99, these pipes connecting with recesses 101. Elbows 103 connect the lower end of pipes 102 with tubular members 104 which are rotatably mounted in sleeve members 105 in the same manner as in the connections described above. Pipe connections 9' extend downwardly from sleeves 105 to the upper end of carrier devices 6 as previously described. 110

It will be seen that the above construction permits the required pivotal movement in the pipe connections as the carrier devices move from one position to the other, the construction also permitting adjustment of the pipe connections toward and away from each other in accordance with the adjustment of the carrier devices toward and away from each other. 115

It will be noted that our invention is not limited strictly to the details of construction described, but is as broad as is indicated by the accompanying drawings.

What we claim is:—

1. In die-casting apparatus, the combination of a molten metal container, a plurality of carrier devices mounted in parallel relation above said container, having hollow interiors, mouths at the front and compressed air connections at the rear, means 125

130

for swinging said devices simultaneously, so that said mouths will be submerged within the molten metal in the container in one position and will be registered with die openings in another position, and means for adjusting the positions of said devices independently.

2. In die-casting apparatus, the combination of a molten metal container, a plurality of carrier devices mounted in parallel relation above said container, having hollow interiors, mouths at the front and compressed air connections at the rear, a transverse shaft, links arranged to swingingly support said devices therefrom at adjustable heights, supporting connections pivotally secured to the forward portions of said devices, and means for swinging said devices simultaneously, so that said mouths will be submerged within the molten metal in the container in one position and will be registered with die openings in another position.

3. In die-casting apparatus, the combination of a molten metal container, a plurality of carrier devices mounted in parallel relation above said container, having hollow interiors, mouths at the front and compressed air connections at the rear, means for swinging said devices simultaneously, so that said mouths will be submerged within the molten metal in the container in one position and will be registered with horizontally arranged die openings in another position, and means for adjusting the positions of said devices, vertically and horizontally, independently.

4. In die-casting apparatus, the combination of a molten metal container, a plurality of carrier devices mounted in parallel relation above said container, having hollow interiors, mouths at the front and compressed air connections at the rear, independent means for supporting said devices, such that the same may be moved laterally bodily of the container and oscillated, so that said mouths will be submerged within the molten metal in one position and will be projected horizontally for registration with die openings in another position of said devices, means for so moving and oscillating said devices together, and means for adjusting the positions of said devices independently, vertically and transversely.

5. In die-casting apparatus, the combination of a molten metal container, a plurality of carrier devices mounted in parallel relation above said container, having hollow interiors, mouths at the front and compressed air connections at the rear, means for swinging said devices simultaneously, so that said mouths will be submerged within the molten metal in the container in one position and will be registered with horizontally arranged die openings in another position, and

means for adjusting the positions of said devices independently towards and away from each other horizontally, towards and away from the die openings, and vertically.

6. In die-casting apparatus, the combination of a molten metal container, a plurality of carrier devices mounted in parallel relation above said container, having hollow interiors, mouths at the front and compressed air connections at the rear, a gate member having a plurality of horizontal openings therethrough, adjacent said container, means for adjusting the position of said member with respect to said container, means for moving said carrier devices simultaneously so that said mouths will be submerged within the molten metal in one position and will be registered with said openings in another position, and means for adjusting the positions of said devices independently.

7. In die-casting apparatus, the combination of a molten metal container, a plurality of carrier devices mounted in parallel relation above said container, having hollow interiors, mouths at the front and compressed air connections at the rear, a gate member having a plurality of horizontal openings therethrough, adjacent said container, means for adjusting the position of said member vertically with respect to said container, bushings in said openings, adapted to be adjusted horizontally therein, means for moving said carrier devices simultaneously so that said mouths will be submerged within the molten metal in one position and will be registered with said bushings in another position, and means for adjusting the positions of said devices independently.

8. In die-casting apparatus, the combination of a molten metal container, a plurality of carrier devices mounted in parallel relation above said container, having hollow interiors, mouths at the front and compressed air connections at the rear, an air supply pipe, pivoted connections between said pipe and the air connections on said carrier devices, comprising horizontal tube members and sleeve members thereon, means for swinging said devices simultaneously, so that said mouths will be submerged within the molten metal in the container in one position and will be registered with die openings in another position, means for adjusting the positions of said devices horizontally, toward and away from each other, and means for correspondingly adjusting the relative positions of said horizontal tube and sleeve members of said pivoted air connections.

9. In die-casting apparatus, the combination of a molten metal container, a carrier device above the same having a hollow interior, a mouth at the front and a com-

pressed air connection at the rear, a transverse shaft, a link arranged to swingingly support said device therefrom, said link having a longitudinal slot therein through which said shaft extends and means for supporting said link from said shaft at an adjusted height, a swinging arm pivotally secured to the forward portion of said carrier device, adapted to support said 10 mouth within the container in one position and above the container in delivery position, and means for adjusting the lateral position of said arm.

10. In die-casting apparatus, the combination of a molten metal container, a carrier device above the same having a hollow interior, a mouth at the front and a compressed air connection at the rear, a transverse shaft, a link arranged to swingingly support said device therefrom, at a desired point lengthwise thereof, an arm pivotally connected to the forward portion of said device for supporting the same and raising and lowering said mouth out of and into 20 the molten metal in the container, a supporting member, means for adjusting the position thereof forward or back and laterally relatively to said container, and a toggle pivotally secured to said supporting 26 member and to said link for swinging the

latter and holding it in forward position in which said mouth is raised.

11. In die-casting apparatus, the combination of a molten metal container, a fixed frame carrying the same, a pair of carrier 35 devices in parallel relation above said container having hollow interiors, mouths at the front and compressed air connections at the rear, a pair of supporting members at the rear of said frame, means for adjusting the positions of the same independently, longitudinally and laterally of said container, swing supporting means pivotally secured to said devices, toggles pivotally secured to said supporting members and to 40 said swing supporting means, a single means for operating said toggles, and a pair of swinging arms pivotally secured to the forward portion of said devices, to support said mouths within the molten metal in 50 the container in one position and above the mass of molten metal, in another position, for delivery of their charges.

This specification signed and witnessed this 23rd day of November, 1920.
